UNITED STATES PATENT OFFICE

HENRY PETER CLAUSEN, OF MOUNT VERNON, NEW YORK, ASSIGNOR, BY MESNE ASSIGNMENTS, TO WESTERN ELECTRIC COMPANY, INCORPORATED, A CORPORATION OF NEW YORK.

TELEPHONE-EXCHANGE SYSTEM.

1,245,438.

Specification of Letters Patent.

Patented Nov. 6, 1917.

Application filed June 7, 1915. Serial No. 32,693.

To all whom it may concern:

Be it known that I, HENRY PETER CLAUSEN, a citizen of the United States, residing at Mount Vernon, in the county of Westchester and the State of New York, have invented certain new and useful Improvements in Telephone-Exchange Systems, of which the following is a full, clear, concise, and exact description.

10 This invention relates to line selectors or connectors, and particularly to means associated therewith for testing the lines. It is especially applicable to connectors of automatic and semi-automatic telephone exchange systems.

It is desirable for traffic reasons in a telephone exchange system to permit certain operators, such as the operators at a toll or long distance switchboard or incoming operators, to establish connections with wanted lines regardless whether they are at the moment busy or idle. Thus in an automatic or semi-automatic exchange it becomes necessary, in order to meet the traffic requirements referred to, to force connections to busy lines in some manner regardless of the testing means at the connectors which ordinarily operate to reject connections to busy lines. It is the object of this invention to enable any connection, available through a connector switch acting under the control of a sender, to be extended to or to be rejected by a busy line, at the will of the operator or other person manipulating the sender, and to automatically apply the busy test condition to an idle line when a connection thereto is established through a connector without regard to the previous test condition of the selected line.

40 In accordance with one feature of the invention the incoming line, *i. e.* the line extending between the sender and the connector, is available not only for controlling the selecting operation but also for controlling the testing means thereof, whereby, if desired, it may be rendered temporarily ineffective. The invention provides, furthermore, a "no test" controlling device or key at the sender, which may be adjusted by the operator before or during the sending op-

eration, and which shall automatically cause a change to occur in the testing means after the line wanted is selected and before said testing means can become effective to reject a busy line connection. The change in 55 the testing means referred to may be rendered effective at the proper time by shunting the high resistance winding of a test relay associated with the line selector so as to make the operation of this relay possible 60 irrespective of the electrical conditions existing on the called line. The test relay when thus energized or some other automatically available means, may be caused to apply the busy test condition to the selected 65 line so that this line, if it had happened to have been idle, will quickly be made busy to other selectors operated in the ordinary way.

The invention will be more fully understood by reference to the accompanying 70 drawings illustrative of the circuits of a semi-automatic system. Figures 1, 2 and 3 are to be placed adjacent one another from left to right in numerical order, and Fig. 4 below Fig. 1. Fig. 1 represents a toll line and 75 connecting apparatus of a toll operator's switchboard, and the circuits of a "cordless incoming" selector; Fig. 2, part of the circuits of a line selector or connector; Fig. 3, diagrammatically, certain portions of the 80 connector structure, part of the circuit connections thereof, and the circuits of the local subscriber's line; and Fig. 4, certain of the 85 circuits of a sender apparatus adapted for manipulation by an operator when associated with the cordless incoming selector of Fig. 1.

For the purpose of producing various circuit changes required at the incoming selector (Fig. 1), there is provided a sequence 90 switch 100. The circuits of the line selector (Fig. 2) also are controlled by a sequence switch 200, and the circuits of the sender (Fig. 4), are provided with a sequence switch 400. In the complete apparatus certain other sequence switch positions than those indicated adjacent to the sequence switch contacts may be used. For example, positions 2 to 12 inclusive of the sequence switch 100 may be utilized for the control of 100

the circuits during the selecting operations of the incoming and line selectors preceding the final or "units" operation of the latter, which occurs in position 13 of the sequence 5 switch 100, position 6 of sequence switch 200, and position 13 of sequence switch 400. As the preliminary selecting operations, however, do not have any special bearing on the invention claimed herein, and for the 10 sake of brevity, a description of the operations which take place in them and the detail circuits involved therein are omitted.

The heavy black lines running through Figs. 1 to 3 inclusive indicate the conductors 15 through which a telephonic circuit may be established from station A of a toll line to station B of a local subscriber's line. This connection in part includes means, such as an answering plug and jack of an automatic 20 switch, by which the call from station A is extended to a connecting circuit 101 of a toll operator's position, and a calling plug 102 and trunk jack 103, by which the call is extended to the circuits of a cordless incoming 25 selector 104 (Fig. 1). The latter connection may be established in accordance with instructions given by an incoming operator to the toll operator over an order wire, as to the particular incoming trunk or 30 selector which the former operator assigns for the connection. By means of such an order wire (commonly used and not shown in the drawings), the toll operator had previously announced to the incoming operator 35 the number of the wanted subscriber's line. When the incoming operator has assigned the trunk, she depresses an assignment key 105 which starts into operation apparatus for temporarily associating a sender apparatus (Fig. 4) to the assigned trunk. The 40 connection between the trunk and the sender may be made through the usual cord finder 401, certain of the contacts of which are shown. The connection having proceeded as 45 stated to the cordless incoming selector 104, and the sender of Fig. 4 having been connected to the incoming trunk, the incoming trunk operator proceeds to effect the operation of the selector switches in the usual 50 way. The operator may, for example, register the number on a series of keys of any known form of sender or controller. Such a keyboard and the detail circuits thereof not being material to the invention are not 55 shown in the drawing, but there is shown for convenience in tracing the sequence of operations the immediate circuit connections of a well-known counting relay sender effecting the operation of the selector switches. 60 Under the control of such a sender the operator may first cause the incoming selector 104 to extend the call to a trunk leading to the circuits of a line selector 301 having access to a group of lines including the particular

line wanted. The operation is effected automatically until the final selector brushes are adjusted to the terminals of this line. 65

The structure and arrangement of the sender has no bearing on the present invention. Preferably it is of the type described 70 in a Patent No. 1,168,319, patented January 18, 1916, to A. E. Lundell, but any other revertive impulse sender; that is to say, a sender which is adjusted to receive a certain number of impulses in response to the operation of selectively operable switching devices, may be used without departing from the spirit of the invention. Obviously, instead of a revertive impulse sender, an impulse sender may be used by means of which 80 the selector switches are directively set.

Only a general outline of the sender arrangement shown in the mentioned patent is given in the drawings, and the operating positions of the sequence switches shown in 85 Figs. 1 and 4 are different from those used in the cited patent. The cord finder X shown in Fig. 2 of the patent, is represented at 401; only two wipers 408 and 409 and two terminals adapted to be engaged by the 90 wipers being shown. These wipers correspond to the third and fifth wipers of the cord finder shown in the mentioned patent.

In order to simplify the circuits shown in 95 Figs. 1, 2 and 3 of the patent, a single circuit is shown extending between the sender and the controlling apparatus of the selector 104, where a plurality of circuits are shown 100 in the patent. Only one sequence switch 400 is shown in Fig. 4 for performing functions 105 which are usually performed by two sequence switches. This sequence switch therefore is a combination of the sequence switches 300 and 400 shown in the patent. Under the control of a circuit including conductor 403 110 and a sequence switch contact 119, the sequence switch 400 may be moved out of position 1. Sequence switch contact 119 is a combination of sequence switch contacts 206 and 208 of the patent, conductor 403 corresponds to conductor 305, and sequence switch 115 spring 404 to sequence switch spring 304 of the patent. Relay 405 corresponds to relay 309 of the patent. In order to simplify the circuits, this relay is shown as controlling the movement of sequence switch 400 out of position 1, although relay 309 does not perform this function. Instead of the energizing circuit including the right-hand winding of relay 309 of the patent, and the holding circuit including the left-hand armature and winding of relay 309, a single circuit is shown including the right-hand top contact of sequence switch spring 404, conductor 410 and sequence switch spring 120. Conductor 410 corresponds to conductor 317, and sequence switch spring 120 to spring 209 125 of the patent. Relay 418 corresponds to re-

lay 403, and relay 417 to relay 402. Conductor 412 corresponds to conductor 244, sequence switch spring 126 to spring 215, and relay 124 to relay 212 of the patent. The 5 conductor 235 and sequence switch contact 234 of the patent which are used when sending impulses beyond the selector shown in Fig. 1 of the patent are left out, conductor 412 and sequence switch spring 126 being 10 used for this purpose. Conductor 411, by means of which sequence switch 100 may be moved into the talking position, corresponds to conductor 245 of the patent, and sequence switch spring 426 to sequence switch spring 15 429 of the patent.

In a manner to be described more in detail later, the test relay 201 (Fig. 2) of the line selector 301 is ordinarily rendered effective immediately after the adjustment of the line 20 selector 301 to test the condition of the selected line. But if it should be desired that the connection shall be established to this line regardless of whether or not it is busy, the high resistance winding of the test relay 25 is short-circuited for allowing this relay to permit all its functions irrespective of the busy condition to the selected line. In a "no test" operation the high resistance winding of relay 201, as will appear more in detail later, is short-circuited a moment after the selector brushes are adjusted, a circuit path being provided for this purpose over the incoming trunk line from the sender (Fig. 4). If it had been desired by the toll 30 operator that the connection be made regardless of the line condition, she would have instructed the incoming operator to that effect, and the latter operator, preferably before operating the sender, would 35 have depressed the "no test" key 402.

More in detail, the operation of the system is as follows:

Subscriber A desiring to initiate a toll call removes his receiver from the switchhook 45 and causes thereby, in the well-known manner, the automatic or manual extension of his line 104 to an operator's cord circuit 101. The operator having learned by means of her telephone set (not shown) the number 50 of the desired subscriber, transmits this number to an incoming or recording operator over an order wire (not shown), and extends the calling line by inserting plug 102 into jack 103 to a trunk line 106, 107, in accordance with instructions received from 55 the incoming operator. A circuit is closed now from ground through resistance 108, sleeve contacts of jack 103 and plug 102, and the coil of relay 109 to grounded battery, 60 and the potential on the multiples of the sleeve of jack 103 is reduced to guard trunk line 106, 107 against other incoming calls. A further circuit is closed from one side of battery 110 through the upper winding of

relay 111, upper contact of relay 112, primary winding of induction coil 113, trunk line 106, tip side of jack 103 and plug 102, cord circuit 101 including the winding of supervisory relay 114, and back through the ring side of plug 102 and jack 103, trunk 65 line 107, primary of induction coil 113, lower contact of relay 112 and lower winding of relay 111 to the other pole of battery 110. Relays 114 and 111 become energized, the former causing the lighting of supervisory 70 lamp 115, and the latter the energization of relay 116.

The incoming operator proceeds now to cause the building up of a connection between the calling substation A and the 80 called substation B. First she depresses her assignment key 105 closing a circuit from ground through key 105, sequence switch spring 117 (in position 1), and power magnet of sequence switch 100 to grounded battery. Sequence switch 100 leaves its first 85 position and moves, under the control of the normal spring 118, into position 13. In position 2 of sequence switch 100 a circuit is closed from ground through sequence switch 90 spring 119, conductor 403, spring 404 of sequence switch 400 (in position 1), and winding of relay 405 to grounded battery. Relay 405 upon energization closes a circuit through its armature and front contact and 95 sequence switch spring 406 for the power magnet of sequence switch 400, and this sequence switch is under the control of its normal spring 407 moved into position 13. After sequence switch 400 leaves its first 100 position relay 405 is maintained energized through the right-hand top contact of sequence switch spring 404, conductor 410 and sequence switch spring 120 to ground. While sequence switch 400 is moving from 105 position 1 to 13, circuits are established, causing cord finder 401 to hunt with its wipers 408 and 409 for conductors 411 and 412 assigned by the incoming operator, and after the cord finder brushes have been set, 110 the incoming operator sends out the first set of numerical impulses designating the called line, and causes, in the well-known manner, switch 104 to engage with its wipers 121, 122 and 123 the contacts in which terminate 115 trunk 202, 203 and 204 leading to the final selector or connector 301. The setting of the selector switch 104 is accomplished before sequence switch 100 reaches position 13.

In position 12 of sequence switch 100 and 120 position 13 of sequence switch 400, a circuit is closed from grounded battery through the coil of relay 124, sequence switch spring 125 (in position 12), sequence switch spring 126, conductor 412, cord finder brush 409, sequence switch spring 415 (in positions 1 to 125 18 and 13), resistance 416, windings of counting relay 417, and back contact and

armature of relay 418, to ground. Relay 124 by attracting its right-hand armature prepares a locking circuit for itself, and when sequence switch 100 reaches its 13th position this locking circuit is completed through sequence switch spring 125 (in position 13 to 17).

- When the wipers of selector switch 104 are set, a circuit is closed from ground 10 through the left-hand armature and front contact of relay 124, right-hand bottom contact of sequence switch spring 127, wiper 121, conductor 202, sequence switch spring 205 (in positions 1 to 7½ and 1, 7), conductor 206 and winding of relay 207 to grounded battery. Relay 207 becomes energized and closes a circuit from ground through its left-hand armature and front contact, right-hand top and left-hand bottom contacts of sequence switch spring 208, and winding of relay 209 to grounded battery. Relay 209 upon energization causes sequence switch 200 to leave its normal position and to move into position 6, by closing a circuit from ground 15 through its left-hand armature and front contact, sequence switch spring 210, and the power magnet of sequence switch 200 to grounded battery. Relay 209 will not become deenergized when sequence 20 switch leaves its first position, as this relay established a locking circuit for itself from grounded battery through its winding, front contact and right-hand armature, resistance 211, test conductor 204, wiper 123, resistance 212 and sequence switch spring 129 to ground. Due to the closure of this circuit the potential on the terminal of conductor 204 is reduced to guard the trunk selected by switch 104 against other selector switches. 25 Relay 207 remains also energized when sequence switch 200 leaves its first position, a circuit being closed from grounded battery, through the winding of relay 207, conductor 206, sequence switch spring 212 (positions 1 to 6), front contact and armature of relay 207, the top contacts of sequence switch spring 205, conductor 202, wiper 121, the right-hand bottom contact of sequence switch spring 127, and the front contact and armature of relay 124 to ground. 30

In position 6 of sequence switch 200, a circuit is closed for elevating-magnet 302 of connector 301 from grounded battery 303 through the winding of magnet 302, conductor 304, sequence switch spring 212, front contact and right-hand armature of relay 207, top contacts of sequence switch spring 205, trunk conductor 202, wiper 121, the right-hand bottom contact of sequence switch spring 127, and front contact and left-hand armature of relay 124 to ground. The elevating magnet 302 attracts its armature 305 and presses thereby brush rod 306 against a roller 307, which is constantly rotating in

the direction indicated by an arrow. The 65 line wipers 308 and 309 and test wiper 310, and the interrupter brushes carried by rod 306, are, under the control of roller 307, caused to move in an upward direction. The wipers 308, 309 and 310 are adapted to engage the contacts of a terminal bank 314 in which subscribers' lines terminate, and brushes 311, 312 and 313 are adapted to engage an interrupter plate 315. 70

When brush 311 engages a conducting 75 segment, in response to each step taken by the brush, relay 417 is short-circuited and causes upon its deenergization the step-by-step release of the impulse sending arrangement (not shown) set by the incoming operator. This short circuit may be traced from ground through the armature and back contact of relay 418, windings of relay 417, resistance 416, right-hand contacts of sequence switch spring 415, 80 cord finder brush 409, conductor 412, sequence switch springs 126 and 125, wiper 122, trunk conductor 203, sequence switch springs 215 and 216, conductor 217, conducting segment 316, brush 311, conductor 317, 85 brush 313, conducting segment 318, conductor 319, sequence switch spring 218 (position 5½ to 6), conductor 219, and front contact and armature of relay 207 to ground. 90

After the impulse sending mechanism has 95 returned to normal and the wipers of connector 301 have been moved a number of steps, as determined by the set position of the impulse sending mechanism, a circuit (not shown) is closed for relay 418. Relay 100 418 attracts its armature and causes sequence switch 400 to move out of position 13 into position 16, sequence switch spring 425 being closed in position 13 of the sequence switch. A circuit is now closed from ground 105 through sequence switch spring 426, cord finder brush 408, conductor 411, sequence switch spring 117 and the power magnet of sequence switch 100 to grounded battery, and this sequence switch is moved into its 110 fourteenth position. Sequence switch 100 is driven out of position 14 into position 16 by a circuit from ground through sequence switch spring 129 (bottom), armature and front contact of relay 116, sequence switch 115 spring 130, and the magnet of the sequence switch to grounded battery. When sequence switch 100 leaves its position 13, the locking circuit of relay 124 is opened at sequence switch spring 126, and relay 124 in turn 120 opens the energizing circuit of the elevating magnet of connector 301, the circuit of the latter being open also at sequence switch spring 127. The circuit of relay 405 is also opened at 120. This relay deenergizes and 125 drives sequence switch 400 into its normal position, the circuit being closed from ground through the armature and back con- 120

tact of relay 405, spring 406 and magnet of sequence switch 400 to grounded battery. When sequence switch 400 leaves its position 16, which happens after sequence switch 200 has moved out of position 7, the operator's sending device and cord finder 401 are restored to normal.

Upon the deenergization of relay 124 and the opening of spring 127 in position 14 of sequence switch 100, relay 207 becomes deenergized and closes a circuit from ground through its left-hand armature and back contact, sequence switch spring 208 (positions 6 and 2 to 10), and the power magnet 15 of sequence switch 200 to grounded battery. Sequence switch 200 is moved into position 7. In this position relay 207 is again energized by a circuit closed from the plus pole of grounded battery through the winding 20 of relay 207, conductor 206, sequence switch spring 205 (positions 1, 7 to 7½ and 1 to 7½, 16), conductor 202, wiper 121, the left-hand contact of sequence switch spring 127, upper back contact of relay 135, and the 25 secondary winding of repeating coil 113 to the minus pole of battery 136. The energization of relay 207 causes sequence switch 200 to move into position 8, the circuit being closed through the left-hand armature and 30 front contact of relay 207 and the right-hand contacts of sequence switch spring 208.

Due to the deenergization of magnet 302, the wipers 308—310 are arrested on the contacts in which the called subscriber's line 35 terminates. The brush rod 306 with wipers 308—310 is maintained in its advanced position by a spring-pressed pawl 324 adapted to engage openings in rod 306.

If the called substation line is idle, *i. e.*, 40 if full battery potential exists on test terminal 325, test relay 201 becomes energized, a circuit being established from grounded battery 326, through the winding of cut-off relay 327, test conductor 328, terminal 325, 45 wiper 310, conductor 329, sequence switch spring 225, low and high resistance windings of marginal test relay 201, and the bottom contacts of sequence switch spring 226 to ground.

50 Relay 201 closes a locking circuit for itself from ground through its upper armature, front contact and low resistance winding, and sequence switch spring 225 to grounded battery 326, the high resistance winding of 55 relay 301 being short-circuited upon the closure of this circuit. The closure of this locking circuit reduces the potential on the multiples of test terminal 325 so as to prevent another test relay 201 from becoming 60 energized and thereby rendering the line of subscriber B inaccessible to other incoming calls.

Relay 201 being energized, a circuit is closed from ground through lower armature

and front contact of relay 201, conductor 65 227, sequence switch spring 210 (positions 8, 14) and power magnet of sequence switch 200 to grounded battery. Sequence switch 200 moves out of position 8 into position 16.

When sequence switch 100 came into position 16 a circuit was closed from grounded battery 137, through sequence switch spring 138, winding of relays 139 and 135, sequence switch spring 140, conductor 141, and front 75 contact and armature of relay 111 to ground. Relay 135 becomes energized; relay 139 however, remains deenergized, its winding being shunted through its armature and back contact, and the armature and back contact of 80 ringing relay 142. When sequence switch 200 comes into position 16, ringing current is applied to the called subscriber's line from ground through upper armature and front contact of relay 135, left-hand contact of 85 sequence switch spring 127, the talking conductors (indicated in heavy lines), the bell at the subscriber's station B, sequence switch spring 143, bottom armature and front contact of relay 135, sequence switch 90 spring 144, winding of ringing relay 142 and ringing current generator 145 to ground. Relay 142 does not become energized until the called subscriber removes his receiver from the switch hook. Upon the energiza- 95

tion of relay 142, the shunt is removed from relay 139; this relay becomes energized and closes a shunt around relay 135. Upon the restoration of the armature of relay 135, the talking conductors are closed at the back 100 contacts of this relay, and the circuit of relay 142 is opened. Relay 139 is maintained energized by a circuit from grounded bat- 105

tery 137 through sequence switch spring 138, winding, armature and front contact of relay 139, sequence switch spring 140, conductor 141, and front contact and armature of relay 111 to ground. Supervisory relay 146 became also energized upon the closure of 110 the talking circuit at the called subscriber's station after relay 135 released its armatures. The circuit for relay 146 leads from the plus pole of battery 136 through the secondary

winding of repeating coil 113, the talking circuit, winding of relay 146, and the secondary winding of the repeating coil to the minus pole of battery 147. A circuit is now closed from ground through the armature and front contact of relay 111, front contact and armature of relay 146, and winding of 115 relay 112 to grounded battery. Upon the energization of relay 112, the circuit of relays 114 and 111 is opened but relay 111 is maintained energized by a circuit from grounded battery 110, through the upper 120

winding of relay 111, resistance 148, lower armature and front contact of relay 112, and lower winding of relay 111 to ground. Due 125

to the deenergization of relay 114 supervisory lamp 115 is extinguished.

After the conversation is finished and the called subscriber hangs up his receiver, relay 146 becomes deenergized and deenergizes in turn relay 112. Upon the release of the armature of relay 112, the winding of relay 111 is again included in its original energizing circuit, and relay 114 thereby causes again the lighting of lamp 115. The operator controlling the cord circuit 101 pulls plug 102 out of jack 103, causing thereby relays 109, 114 and 111 to release. Relay 111, upon deenergization, opens the circuit 15 of relay 116, which by retracting its armature closes a circuit from ground through sequence switch spring 129, armature and back contact of relay 116, and winding of relay 150, which is slow to energize, to ground. Relay 150 closes then a circuit over sequence switch spring 130, and sequence switch 100 is moved over its 18th into its first position. In positions 17 and 18 of the sequence switch, selector 104 is restored 20 in the well-known manner.

When the brush 123 of selector 104 disengages the terminal of conductor 204, relay 209 becomes deenergized and closes a circuit from ground over its left-hand armature and back contact, sequence switch spring 210, and power magnet of sequence switch 200 to grounded battery, and this sequence switch is moved into its 18th position. When sequence switch 200 leaves position 16, the circuit of test relay 201 is opened at 225, and this relay becomes deenergized. Further, a circuit is closed from grounded battery 303, through the winding of release magnet 330, conductor 331, and sequence switch spring 218 to ground. Magnet 330 attracts its armature 332, causing thereby pawl 324 to disengage brush rod 306, and presses the brush rod against roller 333 constantly rotating in a counter-clockwise direction. The roller 45 333 moves the brush rod in a downward direction, and when it reaches its normal position, a circuit is closed from grounded battery through the power magnet of sequence switch 200, sequence switch spring 210, conductor 334, conducting segment 340 of interrupter 315, brush 312, conductor 317, brush 313, conducting segment 318, conductor 319, and sequence switch spring 218 to ground. Sequence switch 200 moves out of 50 position 18 into position 1, and opens the energizing circuit of magnet 330.

The apparatus is now released to normal and ready for use in the building up of another connection.

60 If the called subscriber is busy, the potential on test terminal 325 is reduced so as to prevent the energization of test relay 201 in position 8 of sequence switch 200. A circuit is therefore closed from grounded bat-

tery through the winding of relay 207, conductor 206, left-hand top contact of sequence switch spring 215, right-hand bottom contact of sequence switch spring 216, and upper armature and back contact of test relay 201 to ground. Relay 207 becomes energized 70 and closes a circuit from ground through its left-hand armature and front contact, right-hand contacts of sequence switch spring 208, and power magnet of sequence switch 200 to grounded battery, for moving sequence 75 switch into position 14. Release magnet 330 is now energized, a circuit being closed from grounded battery 303 through the winding of magnet 330, conductor 331, sequence switch spring 230, and back contact and 80 upper armature of relay 201, to ground. Under the control of magnet 330, connector switch 301 is returned to its normal position. A circuit is now closed from grounded battery through the power magnet of sequence 85 switch 200, left-hand bottom contact of sequence switch spring 210, conductor 334, conducting segment 340 of interrupter 315, brush 312, conductor 317, brush 313, conducting segment 318, conductor 319, and left-hand bottom contact of sequence switch spring 218, to ground. Sequence switch 200 moves into position 17, and a busy tone is applied to the calling subscriber's line from 90 235 through the top contacts of sequence 95 switch spring 226.

The apparatus employed in the building up of the connection is restored in the same manner as above described when considering the severing of a connection extended to an 100 idle subscriber.

In order to insure the seizure of the called line irrespective of the electrical conditions existing on the same, prior to the sending out of impulses, the incoming operator depresses the "no-test" key 402 and causes thereby the energization of relay 430, the circuit being from grounded battery 431 through resistance 432, right-hand winding of relay 430. Relay 430 closes from grounded battery 433 through its left-hand winding, armature and front contact and sequence switch spring 434 to ground, a locking circuit, for itself, said locking circuit being maintained closed by sequence switch spring 105 434 from position 1 to 16 of sequence switch 400.

The connection is built up in the same manner as before stated until sequence switch 200 reaches position 8, and sequence 120 switch 100 position 13. A circuit is now closed from ground through the bottom contacts of sequence switch spring 226, high resistance winding of test relay 201, sequence switch spring 240, conductor 241, armature 125 and back contact of relay 207, sequence switch springs 216 and 215, conductor 203, wiper 122, sequence switch springs 125 and

126, conductor 412, cord finder brush 409, sequence switch spring 415, and armature and front contact of relay 430 to ground. The high resistance winding of relay 201 being thus short-circuited upon the closure of the test circuit, this relay becomes energized even in case the test potential on terminal 325 is reduced.

10 The establishment and the release of the connection proceeds in the same manner as above described.

15 It will be seen therefore, that in case the incoming operator depresses the "no test" key 402, test relay 201 becomes effective and 15 performs all its functions (rendering busy of the called line, coöperation in the control of connector 401, etc.), irrespective of the electrical condition existing on the called line.

20 What is claimed is:

1. In a telephone system, a plurality of lines, a plurality of other lines, means for testing said other lines, means for extending one of said lines, a connector controllable over said extended line for selecting one of said other lines, and means also controllable over said extended line for rendering said testing means ineffective.

25 2. In a telephone system, a plurality of lines, a plurality of other lines, means for extending one of said lines, a connector controllable over said extended line for selecting one of said other lines, means actuated under a predetermined electrical condition 35 of the selected other line for controlling said connector, and means controllable over said extended line for causing said last mentioned means to operate irrespective of said electrical condition.

30 3. In a telephone system, a plurality of lines, a plurality of other lines, means comprising selector switches for extending one of said lines, a connector controllable over said extended line to select one of said other 45 lines, means coöperating in the selecting operation of said connector under a predetermined electrical condition of said other line, and means controllable over said extended line for rendering said last mentioned means 50 effective irrespective of said electrical condition.

35 4. In a telephone system, a plurality of lines, a plurality of other lines, selector switches for extending one of said lines, a connector controllable over said extended line for selecting one of said other lines, means for testing said other lines and for co-operating in the control of the selective operation of said connector, and means also 55 controllable over said extended line for rendering said last mentioned means ineffective as to its testing function.

60 5. In a telephone system, a plurality of lines, a connector switch for selecting called

lines, selector switches for extending a calling line to said connector, means for testing the selected called line, and means controllable over said calling line for rendering said testing means ineffective prior to the operation of said connector.

65 6. In a telephone system, a plurality of lines, a connector, selector switches for connecting a calling line to said connector, means controllable over said extended calling line for operating said connector to seize 70 a called line, a test relay associated with said connector and adapted to operate under a certain electrical condition of the selected called line, and means controllable through said extended calling line prior to the seizure 80 of the called line for permitting the operation of said test relay irrespective of said electrical condition.

7. In a telephone system, a plurality of incoming lines, a plurality of outgoing lines, 85 a connector adapted to connect a calling incoming line to an outgoing line under the control of current impulses sent over said incoming line, a test relay having two windings for testing a selected outgoing line, 90 means for operating said test relay under a predetermined electrical condition of the selected outgoing line, and means controlled over said incoming line prior to the operation of said connector for shunting one of 95 said windings to permit the operation of the test relay irrespective of the electrical condition of said outgoing line.

8. In a telephone system, a plurality of lines, operators' positions, means for extending a calling line to an operator's position, trunk lines, selector switches for extending a calling line through any one of said trunk lines, a connector switch, a test relay associated with said connector and having a high 100 and a low resistance winding, means controllable from said operator's position through said extended calling line to operate said connector, and means also controllable from 105 said operator's position through said calling line for shunting the high resistance winding of said test relay prior to the operation of said connector.

9. In a telephone system, a plurality of incoming lines, a plurality of outgoing lines, 115 means for connecting a calling line to one end of a trunk line, a connector at the other end of said trunk line, means controllable over said trunk line for operating said connector to seize a called line, a test relay 120 adapted to be energized over the called line upon the seizure of same, a high and a low resistance winding for said test relay, and means controllable over said trunk line for shunting said high resistance winding prior 125 to the seizure of the called line.

10. In a telephone system, a plurality of incoming lines, a plurality of outgoing lines,

selector switches for extending a calling incoming line, a connector for connecting an extended incoming line to a called outgoing line, means operative under a predetermined 5 electrical condition of the selected outgoing line for controlling the operation of said connector and for rendering the selected outgoing line inaccessible to other incoming

lines, and means controllable over said incoming line for rendering said first mentioned means effective prior to the operation of said connector and irrespective of said electrical condition. 10

In witness whereof, I hereunto subscribe my name this 3rd day of June, A. D. 1915.

HENRY PETER CLAUSEN.
